UNITED STATES PATENT OFFICE.

HENRY H. WAIT, OF ANDERSON, INDIANA, ASSIGNOR, BY MESNE ASSIGNMENTS, TO
MIDWEST ENGINE CORPORATION, OF INDIANAPOLIS, INDIANA, A CORPORATION
OF DELAWARE.

MULTISTAGE TURBINE.

Application filed February 14, 1922. Serial No. 536,531.

To all whom it may concern:

Be it known that I, HENRY H. WAIT, a citizen of the United States, residing at Anderson, in the county of Madison and State 5 of Indiana, have invented a new and useful Multistage Turbine, of which the following is a specification.

It is the object of my invention to produce a multi-stage steam-turbine of the re- 10 entrant type, whereby provision is made for multiple expansion of the steam and the several stages of the turbine are combined within a total axial length materially less than the sum of the axial lengths of the 15 several stages.

In attaining this object, the separate stages are of the general type shown in my prior Patent No. 1,364,012, granted December 28, 1920. There may be any number of 20 these stages, and between adjacent stages I provide a diaphragm in the same plane as the return guides between such stages for receiving the steam from the turbine wheel and directing it back against such turbine 25 wheel for a second impact; and I provide this diaphragm with openings through it provided with nozzles for directing the expanded steam from a higher-pressure wheel against the blades of a lower-pressure wheel.

30 The accompanying drawings illustrate my invention. Fig. 1 is a vertical central section through a two-stage turbine embodying my invention, the parts outside of the turbine wheel and nozzles being shown in elevation; and Fig. 2 is a fragmental sectional development substantially on the line 2—2 of Fig. 1.

The turbine comprises an outer casing 10 within which a plurality of turbine wheels 40 11 and 12 are rotatably mounted. There may be any number of these turbine wheels, though for simplicity only two are shown. These turbine wheels are fixed on a rotatable supporting shaft 13, mounted in suitable 45 bearings 14. The turbine wheels 11 and 12 are provided with the usual turbine blades 15, which may be of any suitable shape for turbine blades. The blades on the successive turbine wheels through which 50 the steam passes are ordinarily of successively larger size because of the reduced pressure resulting from the expansion of the steam in passing through the successive stages, the blades 15 on the low-pressure

turbine wheel 12 thus being shown larger 55 than those on the high-pressure turbine wheel 11.

Steam is supplied, through any suitable manual and automatic controlling devices, to any desired number of nozzle stands 20 with which the casing 10 is provided. These nozzle stands are hollow domes entering the side of the casing, to receive this steam, and ordinarily the steam may be shut off from at least some of these nozzle stands separately for adjustment for different loads, as by a hand valve 21 for the right-hand nozzle stand in Fig. 2. Each nozzle stand 20 is provided with a nozzle 22 which discharges the steam from its nozzle stand obliquely 70 against the blades 15 of the high-pressure turbine wheel 11, as is clear from Fig. 2. The nozzles 22 may be of different sizes, if desired, for convenience in adjusting for the load. On the other side of the high-pressure turbine wheel 11 are arranged a plurality of return guides 23, equal in number to the nozzles 22. These are of the general shape shown in Fig. 2, being provided substantially opposite their associated nozzles 80 with a plurality of steam-receiving passages 24, which at their entrance ends are properly directed to receive the steam discharged from the blades of the high-pressure wheel, and are curved as shown to direct the steam through all of such passages into a return manifold passage 25 which discharges such steam obliquely against the blades 15 of the high-pressure turbine wheel 11 from the opposite side from that against 90 which the nozzles 22 discharge steam against them.

The return guides 23 are located between the high and low pressure turbine wheels. In this same plane is located a diaphragm 95 30, which has suitable openings through it for the return guides 23 and which has tight joints with such return guides and with the casing 10, as by overlapping flanges 31. The steam which escapes from the blades 15 of the high-pressure turbine wheel after passing through such wheel twice, once in each direction, passes into the space 32 in which the high-pressure turbine wheel rotates, and is confined on the high-pressure 100 side of the diaphragm 30.

The diaphragm 30 is provided with a plurality of passages 35 through it, for allowing

the steam from the space 32 to pass through the diaphragm. These passages 35 are usually greater in number than the nozzles 22, to allow for the expanded volume of steam. 5 On the opposite side of the diaphragm 30 from the space 32 each passage 35 is provided with a second-stage nozzle 36, which is usually provided with a plurality of oblique passageways through it for directing the steam obliquely against the blades 15 of the low-pressure turbine wheel 12. The obliqueness of these passageways in the second-stage nozzles in the same circumferential direction as that of the high-pressure nozzles 22, so that the steam discharged therefrom against the blades of the low-pressure turbine wheel will tend to move such turbine wheel in the same direction as the high-pressure turbine wheel is moved. 10 The passages in the second-stage nozzles 36 are properly shaped for the economic conversion of pressure into velocity, but my present invention is not concerned with this particular shape. Steam from these second-stage nozzles is discharged against the blades of the low-pressure turbine wheel at a considerably lower pressure than that of the steam which acts on the blades of the high-pressure turbine wheel, and such steam is 15 therefore of expanded volume. The steam after passing through the blades of the low-pressure turbine wheel is directed by such blades into a second set of return guides 37, which corresponds in general to the return guides 23 but are larger, and have larger passageways, to take care of the expanded volume of the steam. These return guides 37 receive the steam in one direction, and reverse the direction to discharge it back 20 against the blades 15 of the low-pressure turbine wheel 12 from the opposite side from which the second-stage nozzles discharge against such blades; and also discharge obliquely against such blades, as is clear from Fig. 2. The steam which has passed through the blades of the low-pressure turbine wheel 12 passes into the space 38 on the low-pressure side of the diaphragm 30.

From this space 38, the steam may pass 25 through other diaphragms and other stages of the turbine, of any desired number; but for simplicity I have shown only two stages. Therefore, from this space 38, which is the discharge space of the last stage of the turbine, the steam is discharged from the casing 10 through the discharge outlet 39.

By thus providing the diaphragm 30 in the same transverse plane with the return guides 23, it is possible to reduce to a minimum the axial distance between the turbine wheels 11 and 12, and not only to reduce the cost of construction but to make the rotating element more rigid because of the reduced distance between bearings, and thus 30 to make it possible to use a smaller-size shaft

and still keep the normal operating speed below the critical speed. This makes it possible to make the turbine wheels themselves of lighter construction for the same strength. The use of a smaller-size shaft results in a 70 reduction in leakage and wear at the stuffing boxes and a continuous saving in power loss.

I claim as my invention:

1. A multi-stage turbine, comprising a casing, a plurality of turbine wheels mounted to rotate together within said casing, a diaphragm located in said casing in each space between adjacent turbine wheels, and return guides mounted in said diaphragm to receive steam from the adjacent higher pressure turbine wheel and re-direct it against such turbine wheel, and circumferentially spaced steam nozzles also mounted on and receiving steam through said diaphragm to discharge against the adjacent 80 lower pressure turbine wheel. 85

2. A multi-stage turbine, comprising a casing, a plurality of turbine wheels mounted to rotate together within said casing, a diaphragm located in said casing in each space between adjacent turbine wheels, and return guides mounted in said diaphragm to receive steam from the adjacent higher pressure turbine wheel and re-direct it against such turbine wheel, and steam 90 nozzles also mounted on and receiving steam through said diaphragm to discharge against the adjacent lower pressure turbine wheel, said steam nozzles and return guides being interspersed around said diaphragm. 95

3. A turbine, comprising a casing divided by means of a diaphragm into two parts, a turbine wheel mounted in each of said parts, said diaphragm having apertures through it, and steam return guides mounted in and closing some of said apertures and arranged to receive steam from one turbine wheel and direct it back in the opposite direction against the same turbine wheel, said steam 100 return guides projecting into close proximity to the other turbine wheel. 105

4. A turbine, as claimed in claim 3, with the addition that both turbine wheels are spaced from the diaphragm but the steam return guides mounted in the diaphragm project into close proximity to both turbine 110 wheels. 115

5. A turbine, comprising a casing, two single turbine wheels mounted to rotate together within said casing, a diaphragm located in the casing between said two turbine wheels, said diaphragm having apertures through it, and one or more steam return guides mounted in apertures in said diaphragm with substantially steam-tight joints, each steam return guide being adapted to receive steam from one single turbine wheel and to direct it back in the opposite direction against the same turbine wheel. 120

6. A turbine, as claimed in claim 5, with 125

the addition that the last-named turbine wheel is spaced from the diaphragm and from the casing to provide a passageway around such turbine wheel from one side 5 thereof to the other and the steam passes through that turbine wheel an even number of times.

7. A turbine, as claimed in claim 5, with the addition that the steam return guides 10 project beyond the faces of the diaphragm into close proximity to both turbine wheels.

8. A turbine, as claimed in claim 6, with the addition that the steam return guides 15 project beyond the faces of the diaphragm into close proximity to both turbine wheels.

9. A turbine, as claimed in claim 5, with the addition that one or more nozzles are mounted on said diaphragm at apertures therethrough to co-operate with the other 20 turbine wheel from that from which the steam return guides in the diaphragm receive steam, said nozzles projecting into close proximity to the turbine wheel with which they co-operate.

25 10. A turbine, as claimed in claim 6, with the addition that one or more nozzles are mounted on said diaphragm at apertures therethrough to co-operate with the other turbine wheel from that from which the steam return guides in the diaphragm receive steam, said nozzles projecting into close proximity to the turbine wheel with which they co-operate.

35 11. A turbine, as claimed in claim 7, with the addition that one or more nozzles are mounted on said diaphragm at apertures therethrough to co-operate with the other turbine wheel from that from which the steam return guides in the diaphragm receive steam, said nozzles projecting into close proximity to the turbine wheel with which they co-operate.

40 12. A turbine, as claimed in claim 8, with the addition that one or more nozzles are mounted on said diaphragm at apertures therethrough to co-operate with the other turbine wheel from that from which the steam return guides in the diaphragm receive steam, said nozzles projecting into close 45 proximity to the turbine wheel with which they co-operate.

50 13. A turbine, as claimed in claim 9, with the addition that the steam nozzles mounted on the diaphragm overlap circumferentially 55 the steam return guides.

14. A turbine, as claimed in claim 3, with the addition that the steam return guides which project through apertures in the diaphragm are provided with flanges which overlap said apertures in the diaphragm to 60 form tight joints.

15. A turbine, as claimed in claim 5, with the addition that the steam return guides which project through apertures in the diaphragm are provided with flanges which 65 overlap said apertures in the diaphragm to form tight joints.

16. A turbine, as claimed in claim 14, with the addition that the overlapping flanges are on that side of the diaphragm from 70 which the steam return guides receive steam.

17. A turbine, as claimed in claim 15, with the addition that the overlapping flanges are on that side of the diaphragm from which the steam return guides receive steam. 75

18. A turbine, as claimed in claim 9, with the addition that the steam return guides and the nozzles are attached to opposite sides of the diaphragm.

19. A turbine, as claimed in claim 13, with the addition that the steam return guides and the nozzles are attached to opposite sides of the diaphragm. 80

20. A turbine, comprising a casing, a diaphragm dividing said casing into high-pressure and low-pressure stages on opposite sides of said diaphragm, a turbine wheel mounted in each of said stages, said diaphragm having nozzle'd apertures through it for discharging steam against the turbine 90 wheel in the low-pressure stage, steam return guides for receiving steam from one side of the turbine wheel in the high-pressure stage and discharging it back in the opposite direction against the same turbine 95 wheel, said turbine wheel in the high-pressure stage being spaced from the diaphragm and the casing to provide a passageway around said turbine wheel from one side to the other, and the steam passages being arranged so that the steam passes through that turbine wheel an even number of times. 100

21. A turbine, as claimed in claim 20, with the addition that the steam return guides are mounted on said diaphragm. 105

In witness whereof, I have hereunto set my hand at Indianapolis, Indiana, this 13th day of February, A. D. one thousand nine hundred and twenty two.

HENRY H. WAIT.
